CENTRIFUGE

Thomas R. Komline, Ridgewood, N. J., assignor to Komline-Sanderson Engineering Corporation, Glen Rock, N. J., a corporation of New Jersey

Application March 31, 1944, Serial No. 528,879

8 Claims. (Cl. 233—20)

1

This invention relates in general to, and it is an object to provide, an improved centrifuge; the device being generally adaptable in processing industries for the removal of solid matter from water, or thickening or classifying operations. In particular the device is designed for use in connection with the treatment of sewage.

A further object of this invention is to provide a device, for the dewatering and thickening of sludge, garbage, or the like, which is simple, sturdy, safe, and practical in structure and operation; the device being constructed so that it will withstand stresses induced when processing material which is not homogeneous and which may produce a condition of unbalance in the device.

An additional object of the invention is to provide a device of the type described which is operative to discharge the thickened solid matter without stopping the rotary body of such device, or disturbing its other contents; this being an obviously important feature.

A still further object of the present invention is to provide a centrifuge which is operative to handle bulky solids without clogging in the working parts.

Another object of the invention is to incorporate with the centrifuge, a novel receiver and centrifugal discharge unit for the thickened material.

A further object of the invention is to provide a device which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Figure 1 is a sectional elevation of the improved centrifuge.

Figure 2 is a fragmentary transverse section of the rotary body; the solenoid control circuit being shown diagrammatically.

Figure 3 is a transverse section on line 3—3 of Fig. 1.

Referring now more particularly to the characters of reference on the drawings, my improved centrifuge comprises a heavy-duty, U-shaped frame 1 including upstanding pedestals 2 of substantial height. A horizontally disposed, influent or feed pipe 3 is fixedly mounted in connection with one of the pedestals 2, while a horizontal, effluent or discharge pipe 4 is similarly mounted in connection with the other pedestal 2; the pipes

2

3 and 4 being axially aligned and terminating at their inner ends in substantial spaced relation.

A circular rotary body, indicated generally at 5, is disposed between the pedestals 2 and is rotatably supported by the adjacent end portions of the pipes 3 and 4, which in effect form trunnions. At opposite ends the body 5 includes hubs 6 and 7 respectively, said hubs housing antifriction bearings 8 and packing glands 9 which cooperate with the pipes in supporting and sealing relation.

The hub 7 is fitted with a drive pulley 10 which may be driven from a source of power in any suitable manner, as for example a belt drive from an electric motor mounted to one side of the frame 1.

The rotary body 5 comprises the following:

A frusto-conical bowl 11 extends from connection at its small end with hub 6 in radially outwardly flaring relation to connection with a front wall 12 which is annular and radiates from the large end of bowl 11. A circular and radial back wall 13 is secured in connection with the inner end of hub 7 and extends outwardly to a termination at its periphery of the same diameter as that of the front wall 12.

A short distance radially inwardly of the peripheries of walls 12 and 13 the body includes an annular and concentric cross wall 14 having a plurality of equally and circumferentially spaced ports 15 therethrough.

V-shaped separators 16 are secured transversely between the walls 12 and 13 and project radially inwardly from the wall 14 between adjacent ports 15; said separators forming outwardly converging hoppers 17 between walls 12 and 13; each hopper communicating with one of the ports 15. The radial extent of the separators 16 is such that the inner ends of the hoppers are disposed in substantially the peripheral plane of the inner end of frusto-conical bowl 11.

Each of the ports 15 is normally closed by a slide valve 18 mounted exteriorly of the wall 14 for circumferential movement to open or close said ports. The slide valves 18 may be held in place by any suitable means. Circumferentially aligned angularly spaced solenoids 19 are mounted exteriorly on wall 14 between adjacent slide valves 18, with opposed connecting rods 20 on said solenoids secured to corresponding ones of said slide valves. Alternate solenoids actuate in opposite directions, and circuits are employed so that the set of solenoids working in one direction or the set of solenoids working in the other direction may be selectively energized. It will thus be seen that when one set of solenoids is actuated,

the slide valves 18 will all simultaneously open, whereas when the other set of solenoids is actuated all of the slide valves will simultaneously close. Also, by virtue of the fact that the solenoids, connecting rods, and slide valves 18 are connected in endless unitary relation, positive control of the slide valves, without sticking of certain ones thereof, is accomplished.

The circuit arrangement for the solenoids, as indicated diagrammatically in Fig. 2, comprises a pair of circuits indicated generally at 21 and 22. The circuit 21 runs from a slip ring and brush units 23 on hub 6 to one of the terminals of every other one of the solenoids 19, the other terminals of which are connected to the rotary body 5, which, in turn, is grounded as at 29. The other circuit 22 runs from another slip ring and brush unit 23a on the hub 6 to one of the terminals of the other solenoids, the other terminals of which are similarly connected to the ground. 25 is a feed line which, by moving a manually controlled switch 26, can be connected to the slip ring and brush unit 23 or to the slip ring and brush unit 23a. Selective closing of the switches 26 will result in operation of the sets of solenoids in the manner hereinbefore described.

The effluent pipe 44 projects some distance into the rotary body 5, and a concentrically disposed conical baffle 27 of lesser diameter than the bowl 11 is mounted within the latter in clearance and facing relation to the influent pipe 3. As the conical baffle 27 is of lesser diameter than the bowl ample clearance is provided between the baffle and bowl. The baffle is supported by a spider 28 and the effluent pipe 4 terminates at its inner end in substantially the plane of the adjacent end of said baffle.

The walls 12 and 13 extend some distance radially out from the annular wall 14 as flanges 29, and at their peripheries said flanges project into an annular trough 30 with a running fit. Vanes 31 radiate in circumferentially spaced relation from wall 14 between walls 12 and 13, and such vanes extend to the periphery of the latter. The annular trough is formed at the bottom with a tangential discharge pipe 32 opening at its inner end into said trough. The above assembly of flanges 29, trough 30, vanes 31, and pipe 32 form the receiving and discharge unit of the device.

Operation

In operation, the rotary body 5 is driven at relatively high speed, and the sludge or other material to be treated is fed through influent pipe 3 into the bowl 11. The baffle 27 tends to force the material outwardly into engagement with the bowl along which it travels toward the hoppers 17. The centrifugal action causes the solids in the material to deposit in hoppers 17, while the liquid from which such solids have been separated builds up to the rear of baffle 27 and flows out of the body 5 through the effluent pipe 4.

When the hoppers 17 are loaded with solids, the slide valves are opened through the medium of the solenoids and without stopping the rotary body, whereupon the collected solids are fed through ports 15 and into the annular channel C defined by the flanges 29 and trough 30. The vanes 31 carry the solids about said channel C and discharge them through pipe 32. When the hoppers have been substantially emptied the slide valves are closed.

If the thickened material being collected in hoppers 17 remains so viscous that an undue

amount of short-circuiting of the original influent or excessive splashing should occur during the unloading of said hoppers, the influent may be thickened or tempered by the addition of some powder, such as sawdust, dried sludge, coal, or the like thereto. This additive may also be useful to raise the B. t. u. content of the thickened material for a heat balance if incineration is the final goal.

With the above described centrifuge it is possible to thicken and classify materials having bulky solids therein, as the device does not tend to clog. Due to the centrifugal discharging force which is exerted on the solids in the hoppers at all times, the solids are forcefully discharged through the ports 15 when the valves are opened.

In addition, my improved centrifuge is effective with material where the specific gravity of the liquid and solid portions is very nearly the same, and this is true for the reason that there is no undue disturbance of the contents of the rotary body resulting from removal of the collected solids in the hopper.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

1. A centrifuge comprising a frame including a pair of rigid, upstanding legs, influent and effluent pipes mounted on corresponding ones of said legs in fixed relation, said pipes being axially aligned and spaced apart at adjacent ends, a rotary centrifuge body concentric to and extending between said pipes, and means rotatably supporting the body solely from said pipes; said means comprising hubs on opposite ends of said body surrounding corresponding pipes, antifriction bearings between each hub and the surrounded pipe, and packing glands between said hubs and pipes axially inwardly of the bearings.

2. A centrifuge comprising a circular rotatably mounted centrifuge body adapted to be power driven, and influent and effluent pipes in communication with the body at opposite ends; said body including a plurality of circumferentially spaced ports therein, a slide valve normally closing each port, said valves being slidable circumferentially of the body to open or close said ports, solenoids mounted lengthwise on the exterior of the body between the slide valves, connecting rods extending from opposite ends of the solenoids to connection with adjacent valves whereby the valves and solenoids are linked in continuous unitary relation, alternate ones of said solenoids being oppositely acting, and circuit means to selectively actuate said alternate solenoids or the remaining solenoids.

3. A centrifuge comprising a circular rotatably mounted centrifuge body adapted to be power driven, and influent and effluent pipes in communication with the body at opposite ends; said body including a plurality of circumferentially spaced ports therein, a slide valve normally closing each port, said valves being slidable circumferentially of the body to open or close 70 said ports, solenoids mounted lengthwise on the

exterior of the body beyond opposite ends of said valves, the solenoids corresponding to each valve being oppositely acting and connecting to such valve in actuating relation, and circuit means to selectively energize the solenoids which are operative to move the valves in one direction or the other.

4. A centrifuge comprising a circular rotatably mounted centrifuge body adapted to be power driven, and influent and effluent pipes in communication with the body at opposite ends; said body comprising radial front and back walls disposed in adjacent spaced, parallel relation, the front wall having a relatively large diameter circular opening therein in communication with a frusto-conical bowl included in said body, a circumferential cross wall closing the body between the front and back walls radially out from the inner end of the bowl, said cross wall having a plurality of circumferentially spaced ports therethrough, transverse separators in the body between the front and back walls outwardly of the bowl, said separators forming separate, circumferentially spaced material receiving pockets in the body beyond and radially out from the inner end of said bowl, the pockets communicating at their outer ends with said ports, movable valves normally closing the ports, and means to open and close said valves.

5. A centrifuge comprising a circular rotatably mounted centrifuge body adapted to be power driven, and influent and effluent pipes in communication with the body at opposite ends; said body including a frusto conical bowl enlarging in the direction of the effluent pipe, means forming a plurality of circumferentially spaced pockets in the body beyond and radially out from the large end of the bowl, said pockets being in communication at their radially outer ends with ports in the body, normally closed valves on the body cooperating with said ports, and a spider mounted conical baffle of lesser diameter than the bowl disposed in the body and projecting into said bowl; the effluent pipe projecting some distance into the body across the radial plane of said pockets, and the peripheral edge of the conical baffle being disposed in substantially the same radial plane as the inner end of said effluent pipe.

6. A centrifuge comprising a circular rotatably mounted centrifuge body adapted to be power driven, said body including a circumferential wall having a plurality of discharge ports there-

through, valves normally closing said ports, means to open and close said valves, and an annular receiver and centrifugal discharge unit formed in part with and surrounding the body, whereby to receive thickened material from said ports and to discharge the same from a common outlet included in said unit; said annular receiver and centrifugal discharge unit including radially outwardly extending annular flanges on the body on opposite sides of said ports, an annular trough into which said flanges project, impeller vanes mounted between the flanges, and a discharge conduit in communication with and leading from said trough.

15 7. A centrifuge as in claim 6 in which the vanes are disposed between the ports, extend the full width between the flanges, and are of substantially the same height as the latter.

8. A centrifuge comprising a circular rotatably mounted centrifuge body adapted to be power driven, said body including a circumferential wall having a plurality of discharge ports therethrough, valves normally closing said ports, means to open and close said valves, and an annular receiver and centrifugal discharge unit formed in part with and surrounding the body, whereby to receive thickened material from said ports and to discharge the same from a common outlet included in said unit; said annular receiver and centrifugal discharge unit including radially outwardly extending annular flanges on the body on opposite sides of said ports, an annular trough into which said flanges project, and a discharge conduit in communication with and leading from said trough.
